UNITED STATES PATENT OFFICE

MATHEW PAYNE, OF YONKERS, NEW YORK

DESIGN FOR A HYPODERMIC SYRINGE NOZZLE

Application filed December 11, 1930. Serial No. 37,943. Term of patent 14 years.

To all whom it may concern:

Be it known that I, MATHEW PAYNE, a citizen of the United States, residing at Yonkers, in the county of Westchester and State of New York, have invented a new, original, and ornamental Design for a Hypodermic Syringe Nozzle, of which the following is a specification, reference being had to the accompanying drawings, forming a part thereof.

In said drawings:

Figure 1 is a front elevation of the hypodermic syringe nozzle, showing my new design.

Figure 2 is a plan view thereof.

I claim:

The ornamental design for a hypodermic syringe nozzle, as shown.

MATHEW PAYNE.
